BACKSTOP NIPPLE

Burton E. Bailey, Baton Rouge, La.

Application April 1, 1942, Serial No. 437,267

5 Claims. (Cl. 166—1)

This invention relates to back-stop nipples.

An object of the invention is the provision of a nipple adapted to be inserted in an oil well pipe line between the lubricator and the Christmas tree on the oil well derrick for holding or catching falling tools caused by a broken line or blow-out from gas pressure while cutting paraffin or while swabbing the tubing.

A further object of the invention is the provision of a nipple adapted to be placed between the lubricator and the Christmas tree of an oil well derrick having provision therein for holding or catching tools or for serving as a rest for tools when moving the derrick between wells.

A further object of the invention is the provision of a back-stop nipple which is adapted to be used between a lubricator and a Christmas tree of an oil well derrick during the cutting of paraffin or during the swabbing of the tubing for catching falling tools caused by a broken line when said line hits the top of the lubricator or for supporting the tools at various times, the nipple including a kerfed member manually moved to an inoperative position or retained in an operative position by a resilient means across the path of the moving tools.

This invention will be best understood from a consideration of the following detailed description in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a fragmentary vertical section of a back-stop nipple constructed according to the principles of my invention.

Figure 2 is a transverse horizontal section taken along the line 2-2 of Fig. 1.

Figure 3 is a view in perspective of the tool supporting member in the nipple.

Referring more particularly to the drawing, 10 designates a nipple which is in the form of a pipe or tube which is threaded at its upper end as shown at 11 to receive the internal threads of a lubricator. The lower end of the nipple is also threaded as shown at 12 which is adapted to be screwed into the top of the Christmas tree. The pipe is provided at one side with an elongated opening 13 which extends over a greater portion of the length of the nipple. The width of the opening, however, is relatively small as compared to the length.

(CL. 166-1)

A U-shaped housing generally designated by the numeral 20, has side walls 21 and 22 connected by a top portion 23 and inclined end walls 24 and 25. The rim of the housing 20 is welded to the outer wall of the nipple 10 as shown at 26. The periphery of the open end of the member 20 is sheared off at an angle and is curved so that it will conform to the curvature of the nipple 10 and neatly fit the same. The edges of the elongated opening 13 and the nipple 10 are also sheared off at an angle as shown at 27 so that a substantially smooth surface is provided along the areas where the periphery of the housing 20 is welded to the contiguous parts of the nipple.

15 A back-stop generally designated by the numeral 30 is pivotally mounted on a pin 31 supported by side walls 32 and 33 of a U-shaped member 34. The member 30 is kerfed to provide fingers 35 and 36 which extend from an enlarged portion 37 and where an opening 38 is provided to receive the pin 31. The fingers 35 and 36 are spread apart sufficiently that they will substantially close the passage in the nipple 10 when the member 30 is in the position shown in Fig. 1 in full lines.

20 A spring 40 is located within a bushing 41 which is threaded at 42 in a passage in the inclined end wall 24 of the member 20. The inner end of the spring receives a lug 43 projecting outwardly from that portion of the member 30 where the two fingers 35 and 36 merge into the body 37. A flanged ring 44 is placed upon the lug 43 and receives the inner end of the coil spring 40 for aiding in maintaining said inner end in connection with the lug in position. A plug 45 is threaded into the bushing 41 and may be screwed inwardly or outwardly by any suitable tool when said tool engages the hexagonal head 46 that is located exteriorly of the housing 20. This plug 40 is threaded at 47 into the threads of the hollow bushing 41. The spring 40 tends at all times to move the fingers 35 and 36 to an operative position and across the passage in the nipple 10.

25 An operating rod 50 has an inner enlarged portion 51 which is threaded into the internal threads of an externally threaded boss 52 carried by a packing nut or stuffing box generally designated by the numeral 53. The boss 52 as shown at 54, is threaded into a passage in the top 23 of the housing 20 and is also threaded into a passage 55 formed in the top 56 of the U-shaped bearing member 34. The inner reduced end 57 of the operating rod 50 engages a projection 58 on one end of the member 30 so that when the rod 50 is moved inwardly it will

press upon the projection and force the member 30 to the dotted line position against a stop 59 which is formed integrally with the inner face of the end wall 24 of the housing 20. At this time the spring 40 is compressed against the action of the rod 50.

A wheel or manipulating member 60 is secured to the outer end of the rod 50 for moving the rod inwardly or outwardly within the housing 20 and for causing the latch 30 to be moved into an inoperative position or for releasing the said member to the action of the spring 40.

The operation of my device is as follows. In order to insert a tool through the nipple 10 it is necessary to move the rod 50 inwardly so that it will act on the projection 58 and force the member 30 to the inoperative or dotted line position in Fig. 1. If it be desired at any time to support the tools in the nipple 10 it is only necessary to operate the member 60 for moving the rod 50 outwardly so that the spring 40 will force the member 30 and likewise the fingers 35 and 36 inwardly so that said fingers will extend across the path of the travel of the tools in the nipple 10.

When there is danger of the tools falling the member 30 is moved to the position shown in Fig. 1 so that it will obstruct the passageway in the nipple. In view of the fact that the obstructing member is in the form of a kerf the operating wires which carry the tools may be reciprocated through the nipple as desired, but said fingers will be in a position to engage and support a tool which has been released accidentally or which has been slid into the nipple for the mere purpose of retaining the tool in supported relation in the nipple.

The stuffing box 53 which carries the operating rod 50 for the latch or member 30 performs a double function in that it not only prevents the loss of liquids from the nipple 10 but also through the threaded inner end 52 secures the U-shaped supporting member 34 to the housing 20. Thus it will be seen that by partly unscrewing the stuffing box the support 34 and likewise the latch 30 will be released.

I claim:

1. A back-stop nipple comprising a hollow body having an elongated opening in the wall thereof, a housing secured to the wall and enclosing the opening, a U-shaped support in the housing, said support and housing having alined and threaded passages, a stuffing box having the inner end threaded into the alined passages and securing the support to the housing, a pin carried by the support, a latch having a body portion pivoted on the pin and fingers extending from the body at an angle to each other, a resilient means forcing the fingers across the passage in the hollow body for obstructing said passage to prevent tools from passing through the body and means for manually moving the latch to an inoperative position in said body.

2. A back-stop nipple comprising a hollow body having an elongated opening in the wall thereof, a housing secured to the wall and enclosing the

opening, a U-shaped support in the housing, said support and housing having alined and threaded passages, a stuffing box having the inner end threaded into the alined passages and securing the support to the housing, a pin carried by the support, a latch having a body portion pivoted on the pin and fingers extending from the body at an angle to each other, a resilient means forcing the fingers across the passage in the hollow body for obstructing said passage to prevent tools from passing through the body, and means for manually moving the latch to an inoperative position in said body, said manual means being slidably mounted in the stuffing box.

3. A back-stop nipple comprising a hollow body having an elongated opening in the wall thereof, a housing secured to the wall and enclosing the opening, a U-shaped support in the housing, said support and housing having alined and threaded passages, a stuffing box having the inner end threaded into the alined passages and securing the support to the housing, a pin carried by the support, a latch having a body portion pivoted on the pin and fingers extending from the body at an angle to each other, a resilient means forcing the fingers across the passage in the hollow body for obstructing said passage to prevent tools from passing through the body, and means for manually moving the latch to an inoperative position in said body, said manual means being slidably mounted in the stuffing box.

20 4. A back-stop nipple comprising a hollow body having an elongated opening in the wall thereof, a housing secured to the wall and enclosing the opening, a U-shaped support in the housing, said support and housing having alined and threaded passages, a stuffing box having the inner end threaded into the alined passages and securing the support to the housing, a pin carried by the support, a latch having a body portion pivoted on the pin and fingers extending from the body at an angle to each other, a resilient means forcing the fingers across the passage in the hollow body for obstructing said passage to prevent tools from passing through the body, a rod slidably mounted in the stuffing box and having the inner end engaging one end of the latch, the other end located exteriorly of the body, and a manipulating member on the outer end for manually reciprocating the rod for moving the latch to an inoperative position.

30 5. A back-stop nipple comprising a hollow body having a laterally disposed pocket, a latch in the pocket, a support for the latch, means pivotally mounting an intermediate portion of the latch within the support, said latch having a prong portion adapted to extend across the passage in the hollow body to obstruct the passage, means in the pocket tending to force the prong portion across the passage to catch tools inadvertently falling through said passage, a stuffing box mounted in a wall of the pocket, and a rod slid- 40 able in the box, engaging the latch and moving the prong portion into the pocket and entirely out of the passage.

45 6. A back-stop nipple comprising a hollow body having a laterally disposed pocket, a latch in the pocket, a support for the latch, means pivotally mounting an intermediate portion of the latch within the support, said latch having a prong portion adapted to extend across the passage in the hollow body to obstruct the passage, means in the pocket tending to force the prong portion across the passage to catch tools inadvertently falling through said passage, a stuffing box mounted in a wall of the pocket, and a rod slid- 50 able in the box, engaging the latch and moving the prong portion to an inoperative position entirely within the pocket, said stuffing box having means for removably connecting the support to the body.

BURTON E. BAILEY.
